J. F. EWELL.
UNDERBODY FOR TANK CARS.
APPLICATION FILED APR. 13, 1914.

1,119,261.

Patented Dec. 1, 1914.

UNITED STATES PATENT OFFICE.

JOHN FRANKLIN EWELL, OF CHICAGO, ILLINOIS, ASSIGNOR TO BARRETT MANUFACTURING COMPANY, OF CHICAGO, ILLINOIS, A CORPORATION OF WEST VIRGINIA.

UNDERBODY FOR TANK-CARS.

1,119,261.

Specification of Letters Patent.

Patented Dec. 1, 1914.

Application filed April 13, 1914. Serial No. 831,465.

To all whom it may concern:

Be it known that I, JOHN FRANKLIN EWELL, a citizen of the United States, and a resident of the city of Chicago, in the county of Cook and State of Illinois, have invented a certain new and useful Improvement in Underbodies for Tank-Cars; and I do hereby declare that the following description of my said invention, taken in connection with the accompanying sheet of drawings, forms a full, clear, and exact specification, which will enable others skilled in the art to which it appertains to make and use the same.

15 My invention relates generally to improvements in an underbody for tank cars, and it consists, essentially, in the novel and peculiar combination of parts and details of construction, as hereinafter first fully 20 set forth and described and then pointed out in the claims.

This invention has for its object the provision of a structure which will possess a certain resiliency so as to partially dissipate 25 the strains and stresses peculiar to tank cars.

In the drawings already referred to which serve to illustrate my said invention more fully, Figure 1 is a fragmentary side elevation of one end of a tank car illustrating 30 the coöperation of the tank with the underframing. Fig. 2 is a vertical section taken along line 2—2 of Fig. 1. Fig. 3 is a similar view taken along line 3—3 of Fig. 1 to illustrate the bolster construction.

35 Like parts are designated by corresponding characters or symbols in all the figures of the drawings.

Reference being had more particularly to the drawings, A indicates generally a girder 40 extending throughout the entire length of the car and which constitutes the main support for the tank 10. This girder A is composed of the vertical channel bars 11 secured together along their upper flanges at 45 intervals by the top plates 12 bolted or riveted to the said flanges; and along their lower flanges by the bottom plate 13 which is located medially of the length of the girder A. Located a suitable distance from 50 car bolster B, described and claimed in a co-pending application No. 831,464 and riveted transversely of girder A is a channel bar 14 which has a timber saddle 15 secured therein. Since Fig. 1 only illustrates one 55 end of the car, the other end being a dupli-

cate of the one shown, there are a plurality of the channel bars 14 which are equally spaced one from the other. These saddles 15 support and carry the tank which is guyed or steadied by the guy rods 16. A running board 17 is carried on each side of the tank 10 by the protruding ends of the channel bars 14 and the bolster structure (indicated generally as B). A plate 18 extends from each end of each channel bar 14 to the adjacent side of the girder A where it is secured to the lower flange thereof. This plate acts as a support for the extreme ends of the channel bars 14 and at the same time partially dissipates the strains and stresses 60 set up. The plates 18 are rigidified by the diagonal struts 19 interposed between said plates and the undersides of the channel bars 14.

Fastened to the top flanges of channels 11, 75 between bolster B and channel bar 14 or between adjacent bars 14 are a pair of longitudinal Z-bars 20, the lower legs of which are inwardly pointed and maintained in place by rivets closely spaced. The upper 80 legs of these Z-bars are bent upwardly on an arc of a circle so as to form a central, rigid, fastening of the tank to the girder A. These bars are first riveted to the girder A and then the tank is seated on said bars and 85 riveted thereto. Said Z-bars 20 have their opposite ends closely abutting the bolster B and the channel bar 14, or adjacent bars 14, as clearly seen in Fig. 1, thereby presenting 90 resistance to end movement of said Z-bars, in addition to the rivets by which they are fastened to the girder A. It is thus observed that the tank is rigidly fastened to the girder medially of its length by riveted members, the strength of which is sufficient 95 to prevent any end movement of the tank on the girder. But exteriorly of this riveted section the girder may weave or twist considerably as the track road bed varies, without imparting undue stresses upon the tank 100 proper.

While herein I have disclosed the preferred method of practising my invention, I desire it understood that I may make such changes and alterations therein as might 105 suggest themselves to the skilled mechanic or permitted under the doctrine of equivalents.

Having thus fully disclosed my invention, I claim as new and desire to secure to 110

myself by Letters Patent of the United States:—

1. The combination with a longitudinal girder of a plurality of transverse members thereon, a Z-plate on each side of said girder between adjacent members, the opposite ends of said Z-plates abutting said members, and a tank fixed to said Z-plates.
2. The combination with a longitudinal girder of a bolster adjacent each end thereof, a plurality of transverse bars secured to each girder intermediate of its end, and a Z-plate secured on each side of the girder aforesaid between each bolster and its adjacent bars.
3. The combination with a longitudinal girder of a bolster adjacent each end thereof, a plurality of transverse bars secured to each girder intermediate of its end, a tank,

and a Z-plate on each side of the girder 20 aforesaid and between each bolster and its adjacent bar for supporting said tank.

4. The combination with a longitudinal girder of a bolster adjacent each end thereof, a plurality of transverse bars secured to 25 each girder intermediate of its end, a tank, and a Z-plate on each side of the girder aforesaid and between each bolster and its adjacent bar, having one web secured to said tank and the other to the adjacent side of 30 the girder.

In testimony whereof I have hereunto set my hand in the presence of two subscribing witnesses.

JOHN FRANKLIN EWELL.

In the presence of—

RICHARD MACKAY,
C. S. STARK.
